UNITED STATES PATENT OFFICE.

JACOB J. BYERS, OF CHICAGO, ILLINOIS, ASSIGNOR TO THE NATIONAL MALLEABLE CASTINGS COMPANY, OF CLEVELAND, OHIO, A CORPORATION OF OHIO.

TIE-PLATE.

1,069,386.

Specification of Letters Patent. Patented Aug. 5, 1913.

Application filed January 3, 1912. Serial No. 669,202.

To all whom it may concern:

Be it known that I, JACOB J. BYERS, a resident of Chicago, in the county of Cook and State of Illinois, have invented a new and useful Improvement in Tie-Plates, of which the following is a full, clear, and exact description, reference being had to the accompanying drawings, forming part of this specification, in which—

10 Figure 1 is a diagrammatic plan view showing the preferred positions of my improved plates and anchors in a railroad track; Fig. 2 is a side elevation showing my improved plate and anchor in place; 15 Fig. 3 is a top plan view of the preferred form of tie-plate; and Fig. 4 is a perspective view showing a single form of plate which I may employ.

My invention relates to the use of rail anchors or anticreeping devices in railroad tracks, and is designed to do away with the necessity for tie-engaging projections on such anchors or anticreeping devices.

To that end, the invention consists in arranging a tie-plate so that it will act as an abutment for the rail anchor, or at least, the stationary member thereof, where the anchor has more than one member.

The invention also consists in providing a double tie-plate which will avoid the necessity for two anchors opposite the joint of a track, in order to hold the ties in proper position.

In the drawings, referring to Fig. 1, a represents a joint or joints of one line of rails, being alternate or staggered relative to those of the other line of rails. It has been customary to place the two anchors or anticreepers intermediate the length 40 of one rail at a point opposite the joint a, as indicated at b, b in Fig. 1. It has also been customary to place the rail anchor at the quarter length of the rail, as indicated at c in Fig. 1. These anchors have been provided with tie-engaging projections which engage the body of the tie.

In carrying out my invention, I am able to keep the two ties in line opposite a rail joint by employing a double tie plate marked 2, one end of which is provided with a depending rib or abutment 3, against which the rail anchor, such as shown at 4, abuts. This tie plate bridges two ties, and

is provided with spike holes 5, which may be arranged in any desirable manner, although I preferably arrange them in pairs in each portion of the tie plate, as shown. This tie-plate may be provided with rail abutments, indicated at 6, if desired, to engage the side edges of the base flange of the rail; and if desired, I may employ a transverse depending abutment 7, to engage the other of the two ties, although this may or may not be used, as desired, and is not necessary. The intermediate portion 2^a of this tie-plate is preferably reduced in cross section, as indicated in Fig. 3, by cutting inwardly at the sides, or this may be made lighter by thinning this connecting portion and employing strengthening ribs, if desired.

In Fig. 4, I show a single form 8 of the tie-plate having the same end abutment or rib 9, to serve as an abutment for the anchor 4^a. This may be used at the quarter length of rail, where a single anchor has been commonly employed or at any intermediate point desired.

The advantages of my invention result, first, from the use of a tie-plate which is shaped to form the abutment for the rail anchor or anticreeping device, as this does away with the need of projections in the rail anchor to engage the tie; also from the use of the double plate which bridges two ties, acts as an abutment for the rail anchor and requires only one rail anchor to hold the two ties in position. Different types of rail anchors or anticreeping devices may be employed, and the form and size of the tie-plate may be varied widely without departing from my invention, since I consider myself the first to arrange a tie-plate so that it will act as the abutment for the rail anchor.

I claim:

1. A railroad track having a tie plate positioned under the intermediate portion of a rail opposite the joint of the other line of rails, said plate bridging two ties, a rail anchor abutting against one end of said tie plate, and an intermediate tie plate and anchor co-operating therewith at an intermediate part of the rail not opposite a joint; substantially as described.

2. A railroad track having a tie plate

positioned under the intermediate portion of a rail opposite the joint of the other line of rails, said plate bridging two ties, a rail anchor abutting against one end of said tie plate, and an intermediate tie plate and

ends-of the longer and shorter tie plates; substantially as described.

10

In testimony whereof, I have hereunto set my hand.

JACOB J. BYERS.
